Attorneys,

UNITED STATES PATENT OFFICE.

GUSTAVE MACQUART, OF RED BLUFF, CALIFORNIA.

RAILROAD-SIGNAL.

SPECIFICATION forming part of Letters Patent No. 268,916, dated December 12, 1882.

Application filed January 5, 1882. Renewed November 16, 1882. (No model.)

To all whom it may concern:

Be it known that I, GUSTAVE MACQUART, a citizen of the United States of America, residing at Red Bluff, in the county of Tehama and State of California, have invented certain new and useful Improvements in Railroad-Signals; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, wherein—

15 Figure 1 is a perspective view of my improvements attached to a railroad-track, and Fig. 2 is a detailed view of the device.

This invention has relation to improvements in railroad-signals; and it has for its object to 20 provide a danger-signal which will, under the conditions hereinafter set forth, notify the engineer or lookout on a train of cars of "wash-outs" on the road or caving in of a tunnel or the breaking of a bridge.

25 My invention consists in a tube fixed to the cross-ties of a railroad-track, and having inserted therein a rod or wire, the ends of which are attached to the eyes of spring bolts or catches, in combination with a signaling device, as hereinafter described.

My invention further consists in the combination, with a railroad track and tubing running parallel with the rails, of a rod or wire in 30 said tube, a spring bolt or catch, and a signaling device.

35 My invention further consists in the novel construction and combination of parts, as will be hereinafter more fully set forth and specifically claimed.

40 In the annexed drawings, the letter A represents a railroad-track of the usual construction.

The letter B represents a tube running parallel with the track, and fixed to the cross-ties by any suitable means. In this tube, preferably metal, is inserted a metallic rod or wire, *a*, somewhat smaller than the bore of the tube, so that it may easily move therein. Each end of this rod or wire is rigidly secured to the eye of a bolt or catch.

45 The letter C represents a spring bolt or catch, which may be fixed on a cross-tie of the track,

or preferably boxed securely and sunk below the bed of the track. Two of these bolts are used, substantially as seen in the drawings.

The letter D represents an automatic signal 55 pivotally supported, so that the ball on the ground end of the signal-bar shall be heavier than the bar and signal above the bearing, and is so arranged as to swing at right angles to the line of road, and is set so that when drawn 60 in a position indicating "safety" the lower arm shall engage with the end of the bolt, and be held in that position until released.

The signaling device is of usual construction, and is preferably set in the same box as the 65 spring bolts or catches to give security against accident or unwarranted displacement.

The operation of my improved signal is automatic, and occurs whenever any displacement of the track takes place, occasioning sufficient movement of the tube and rod to pull the bolts from engagement with the arms of the signals, which being thus freed, the signals are carried from "safety" position to "danger" by the weight on the other end of the signal-bar. For instance, if a wash-out or slide happens and the track is destroyed or misplaced, the disturbance must necessarily carry with it the tubing and wire, and in doing so the bolts will be pulled, which will release the signal-bars. Again, if the device is laid on a bridge and the bridge is destroyed or broken or slides, the bolts are drawn and the signals freed; and if in a tunnel a "cave in" occurs and the débris strikes the tube, it is moved and the bolts 85 are drawn from place.

It will be observed that the tubing should be of such size as not to be so strong as to resist great strain, and the rod or wire should be suited to draw the bolt on any occasion 90 arising by accident.

The signals should be placed at such distance from the place to be guarded as to insure stopping a train running at full speed before reaching the point of danger. The accompanying drawings show the signals in an inclined position indicating "safety;" but it is obvious to those skilled in the art that the parts may be so organized and arranged that the signal devices can assume vertical positions to 95 indicate "safety" and the inclined positions "danger." This is a matter entirely discre-

tionary with the road managers, and either mode, vertical or inclined, of indicating danger may be employed.

I reserve the right to slightly vary the construction of the device without departing from the spirit of the invention.

What I claim as my invention, and desire to secure by Letters Patent, is—

1. In a railroad-signal, a tubing secured to the cross-tie of a railroad-track and having inserted loosely in the bore of the tubing a metallic rod or wire, in combination with spring bolts or catches attached to the ends of the rod or wire, and a signaling device, substantially as described.
2. In a railroad signaling device, a metallic tubing fixed to the cross-ties of a railroad-track, having a metallic rod or wire inserted through said tube, the ends whereof are fastened to

bolts or catches, in combination with a signaling device, substantially as described.

3. In combination, with a railroad-track and metallic tubing running parallel with the rails, of a metallic rod or wire running through said tube, a spring bolt or catch, and a signaling device, substantially as described.

4. The combination, with a railroad-track, of a metallic tubing running parallel with the track and fixed to the cross-ties thereof, a rod or wire in said tube having the ends attached to bolts or catches, and a signaling device, substantially as described.

In testimony whereof I affix my signature in presence of two witnesses.

GUSTAVE MACQUART.
